UNITED STATES PATENT OFFICE.

CHARLES R. FARGO, OF CHICAGO, ILLINOIS, ASSIGNOR TO WILSON-JONES LOOSE LEAF COMPANY, A CORPORATION OF ILLINOIS.

LEAF UPSETTING AND SUPPORTING DEVICE.

Application filed August 13, 1917. Serial No. 185,976.

To all whom it may concern:

Be it known that I, CHARLES R. FARGO, a citizen of the United States, and a resident of the city of Chicago, in the county 5 of Cook and State of Illinois, have invented certain new and useful Improvements in Leaf Upsetting and Supporting Devices; and I do hereby declare that the following is a full, clear, and exact description of the 10 same, reference being had to the accompanying drawings, and to the numerals of reference marked thereon, which form a part of this specification.

It is becoming the custom in many businesses to do away with pen bookkeeping and adopt what is commonly called machine bookkeeping. In some machine bookkeeping systems, the accounts are kept on sheets loosely arranged in a drawer with 20 suitable guide cards resembling an ordinary letter file. Heretofore much inconvenience and annoyance, as well as loss of time, has been occasioned by the position the sheets assume when standing on edge in a flat bottomed box of this character making it difficult for the operator to successively remove each sheet or leaf from the body of sheets or leaves. This is due to the fact 25 that the leaves, when inclined to the rear of the file, preparatory in posting assume a position in which the leaves nearest to operator are lower at their tops than the succeeding leaves. This is due to the inclination of the leaves at the bottom, making it 30 necessary to reach around the sides of the leaves or thumb them at the corners in selecting the account sheet to be posted.

It is an object of this invention to provide an upset and supporting device for 40 current use in connection with loose leaf machine posting in which a number of leaves may be "upset" so that their top edges assume a sharp angle inclined away from the operator thus making the edges of the front leaves higher than those behind. The 45 result of this is that the operator may finger the leaves at the top edges, one at a time

greatly facilitating the selection accounts and doing away with the thumbing which requires the employment of two hands. 50

It is further an object of this invention to provide an upset device and supporting device for sheets which is adapted to be inserted in the drawer at any desired position, upon which a suitable number of leaves may 55 be placed and which is automatically adjusted in the drawer by the weight of the leaves as they are shifted from one side to the other.

It is further an object of this invention 60 to provide a device of the class described which is adapted to support leaves thereon with the leaves next to be used elevated, and which is adapted to have all of the leaves placed therein at the proper time, and is 65 adjustable longitudinally in the drawer so that the leaves from the rear may all be successively posted and then placed in the drawer in front of the upset and supporting device so that when the posting is finished 70 all the leaves are in their place and the device may be removed or inserted in a suitable space in the back of the drawer.

It is further an object of this invention 75 to provide an upset and supporting device which may be inserted in any drawer or receptacle containing loose leaves for the purpose herein specified, which has an adjustable member adapted to assume the angle of inclination that the leaves assume and 80 which may be readily removed when the posting is completed or whenever desired.

It is a further object of this invention to provide an upset and supporting device 85 which will completely separate the posted and unposted leaves, thereby preventing them from binding against each other at the bottom.

It is a further object to provide a W shaped arrangement by means of the upset 90 and supporting device thus giving in effect two trays in which the posted and unposted leaves lie on their sides thus permitting the use of light weight ledger papers

which do not curl on the platen of the machine like cards or sheets of heavy weight ledger.

Other and further important objects of this invention will be apparent from the disclosures in the specification and drawings.

The invention (in a preferred form) is illustrated in the drawings and hereinafter more fully described.

On the drawings:

Figure 1 illustrates a closed drawer or receptacle containing loose leaves, provided with an upset and supporting device embodying my invention, showing the same stored in the compartment at the rear of the leaves.

Figure 2 illustrates the use of the same at the beginning of the posting.

Figure 3 is a transverse section taken through the drawer with the sheets in front elevation.

Figure 4 is a transverse section taken through the drawer at the rear thereof.

Figure 5 is an enlarged fragmentary view similar to Figure 2, showing the use of the device as the posting operation proceeds.

Figure 6 is a similar view showing the posting at a more advanced stage.

Figure 7 is a front view of the back plate of the upsetting device.

Figure 8 is a sectional detail illustrating the assembly of the back plate with the upsetting device.

Figure 9 is a sectional view of the back plate, detached.

As shown on the drawings:

The drawer is shown as metallic, and comprises a receptacle or drawer 1, provided with a cover 2. A plate or partition 3, is hinged to the bottom of the drawer and is held in upright position when desired by a latch 4, which is hinged to the drawer and adapted to be swung outwardly when desired, as shown in Figures 5 and 6. For the purpose of clamping the sheets or leaves in place when not in use, a partition plate 5, is placed at the rear of the leaves 6, and a clamping member is adjustably secured in

the drawer at the rear of the plate 5. Said clamping member comprises a channel bar 7, having its ends 8-9, engaging on the flange or bead 10, of the drawer, and a channel member 11, having its ends 12, en-

gaging beneath the flange or bead 10, and a clamp bolt and nut 13, firmly clamp the same in place. As shown, the front wall 14, of the channel member 11, extends downwardly to near the bottom of the drawer.

The upset and supporting device may be made of metal or other suitable material, and is of a length a little less than the width of the drawer or box to fit loosely therein. Said device as shown, is constructed of a plate of metal and is shaped or bent at sub-

stantially a right angle having two oppositely disposed inclined walls 15-16. Integral with the lower edge of the wall 16, are hinge lugs 17, adapted to engage detachably in apertures 18, in a back plate 19, to thereby hingedly connect the plate or table to the upset or supporting device. The back plate 19, may be provided with a lug 21, for engagement with the underside of the wall 16. The rearward movement of the plate 19, beyond the position shown in dotted lines in Figure 8, is prevented by the lugs 17, engaging the rear face of the plate 19, and by the lug 21 contacting with the underside of the wall 16. The plate 19, may be detached from the wall 16, by moving it forwardly into contact with the wall 16, and then sliding the lugs 17, out of the apertures 18. In this position, the lug 21, is clear of the lower edge of the wall 16.

The operation is as follows:

When through posting, the leaves are clamped between the partitions 3 and 5, by means of the clamp, and where the room permits, the upset and supporting device is placed in the drawer at the rear of the leaves, as shown in Figure 1. When it is desired to post or otherwise inspect or handle the leaves, the upset and supporting device is removed, the latch 4, swung up, and the clamp adjusted to the rear of the drawer, as shown in Figure 2. In this position, the leaves are all swung or inclined back and the upset and supporting device is inserted at the front of the leaves. A suitable quantity of leaves are then placed upon wall 16. Owing to the forward and upward inclination of the wall 16, of the device, the front leaves 20, (Figures 2 and 5), are projected above the successive rear leaves, and when the front leaf 20 is removed, the next immediate leaf will be exposed elevated above the successive rear leaves and so on until all the leaves on the device have been posted or otherwise attended to.

After the bunch of leaves have been posted and transferred from wall 16 to wall 15, another bunch of leaves is removed from behind the device and placed on wall 16 providing a space which permits the weight of the leaves on wall 15 to automatically force the device along the bottom of the drawer to occupy this space and the leaves on wall 15, drop onto the bottom of the drawer, as shown in Figures 5 and 6. The hinged back wall or table 19, of the tray, is adapted to automatically assume any degree of inclination that the leaves assume, depending of course, upon the number of loose leaves in the drawer. Furthermore the degree of inclination of the back plate 19, is determined by the adjustment of the follower 14, as it is evident that as the follower approaches or is moved towards the

pivotal axis of movement of the plate 19, comprising a movable member adapted to be laid in the holder, and slide along the bottom thereof, said member having a rearwardly inclined upper face for supporting a portion of the leaves at successively higher elevations, and having a front face adapted to be engaged by leaves disposed at the front thereof so as to slide the member rearwardly along the bottom of the loose leaf holder. 70

One of the great advantages of this device is that it causes the leaves 20, next to be used to be in such position that they may be readily fingered without contacting other leaves. In many other devices heretofore in use, the leaves are exceedingly difficult to finger and usually it is necessary to make several attempts before the desired leaf is secured. Furthermore, by the use of this tray, the leaves that are disposed of are positively inclined toward the front, and cannot fall rearwardly thereby getting continually in the way; in other words, the rear leaves are held and projected into position to be readily removed and the disposed of leaves are held in such position as to preclude them falling back onto the unposted leaves. 75

Of course, the inclination of the walls of the tray may be varied to suit the requirements, and the tray may be changed through a wide range and many details may be varied without departing from the principles of my invention. I therefore desire to claim 80 a device of the class described, broadly and do not desire to limit the patent granted otherwise than necessitated by the prior art.

I claim as my invention:

1. The combination of leaf upsetting means for a loose leaf receptacle, comprising an independent device adapted to be placed in the receptacle so as to support the leaves thereon at successively higher elevations. 85

2. The combination with a loose leaf receptacle, of a removable leaf upsetting device therefor adapted to be laid in the receptacle and support leaves thereon, so that the upper edges of the leaves are at successively higher elevations. 90

45 3. The combination with a holder for loose leaves, of a leaf upsetting device therefor comprising a removable member adapted to be deposited in the holder, said member having an inclined upper face adapted to engage the lower edges of the leaves, and support successive leaves at increasingly higher elevations. 95

4. The combination with a loose leaf receptacle, of an upset and supporting device 100 movable in the receptacle, and having oppositely inclined upper faces, and a back plate hinged thereto and movable therewith.

5. In a device of the class described, the combination with a receptacle containing 105 loose leaves, of an upset and supporting device therein adapted to support leaves thereon, and adjustable in the receptacle automatically by the disposed-of leaves.

6. The combination with a holder for loose 110 leaves, of a leaf-upsetting device therefor

7. In a leaf upsetting device for a loose leaf receptacle, the combination of a member slidable along the bottom of the receptacle and having an inclined upper face for supporting leaves in the receptacle at successively higher elevations, and a back plate 80 supported on said member and movable therewith to afford a lateral support for the leaves on said inclined face.

8. In a device of the class described the combination with a loose leaf receptacle, of a leaf-upsetting member slidable over the bottom of the receptacle, and a back plate 85 detachably mounted on said member and movable therewith.

9. The combination with a loose leaf receptacle, of a leaf-upsetting member loosely supported at the bottom of the receptacle and adapted to be held, by engagement of leaves with opposite sides thereof, in the required relative position to support a portion of the leaves so that each of said leaves is at a successively higher elevation. 90

10. The combination with a loose leaf receptacle, of a leaf-upsetting device in the receptacle having a back plate co-operating therewith to afford a lateral support for the leaves on the upsetting member, and a follower adjustably mounted in the receptacle and adapted to regulate the inclination of the back plate. 100

11. The combination with a loose leaf receptacle having a longitudinal guide at each side thereof, of a follower movable along said guide and comprising a pair of transverse members engaging the guides, one of 110 said transverse members being adjustable to and from the other transverse member to clamp the guides between the transverse members and lock the follower in adjusted positions. 115

12. In a receptacle for loose leaves, a removable upset and supporting device having inclined walls integrally connected, and a back plate hinged thereto.

13. In a device of the class described, a 120 removable upset and supporting device having inclined walls integrally connected, and a back plate detachably hinged thereto.

14. A posting tray comprising a casing having a hingedly mounted front panel, a follow-block mounted within the casing for longitudinal sliding movement, a longitudinally movable upset angle member disposed within the casing and including a relatively sharp angular portion adapted to support 125 130

the lower edges of sheets resting on said angle member.

15. The combination with a receptacle having an inclinable support at one end, a
5 removable leaf-upsetting device slidable relatively to said support and comprising a member having upwardly converging surfaces for forming oppositely disposed leaf supports.
- 10 16. In a device of the class described, a pair of inclinable and relatively adjustable

supports, and a removable leaf-upsetting device shiftable between said supports, said device having upwardly converging surfaces for the purpose described.

15 In testimony whereof I have hereunto subscribed my name in the presence of two subscribing witnesses.
